(57) **CLAIM**

The ornamental design for an electronic device with animated graphical user interface, as shown and described.

DESCRIPTION

1. Electronic device with animated graphical user interface

1.1 : First front view

1.2 : Second front view in changed state

1.3 : Third front view in changed state

1.4 : Enlarged view of Fig. 1.1, provided for clarity of illustration

1.5 : Enlarged view of Fig. 1.2, provided for clarity of illustration

1.6 : Enlarged view of Fig. 1.3, provided for clarity of illustration

The evenly spaced broken lines show an electronic device and the unevenly spaced broken lines define the bounds of the claimed design; all broken lines form no part of the claimed design. The appearance of the transitional image sequentially transitions between the images shown in reproductions 1.1-1.3; the process or period in which one image transitions to another image forms no part of the claimed design.
